UNITED STATES PATENT OFFICE.

JAMES BATE, OF YPSILANTI, MICHIGAN.

DIE-CASTING MACHINE.

Application filed February 13, 1922. Serial No. 536,207.

To all whom it may concern:

Be it known that I, JAMES BATE, a citizen of the United States, residing at Ypsilanti, in the county of Washtenaw and State of Michigan, have invented new and useful Improvements in Die-Casting Machines, of which the following is a specification.

This invention relates to die casting machines of the direct air type, and comprehends certain new and useful improvements hereinafter described and particularly pointed out in the appended claim.

The nature and advantages of the invention will be better understood when the following detailed description is read in connection with the accompanying drawings, the invention residing in the construction, combination, and arrangement of parts as claimed.

20 The figure in the drawing is a view in elevation of the machine partly in section.

Referring to the drawing in detail, 10 indicates a casing or fire box in which is arranged a metallic pot or receptacle 11, the latter reposing upon the upper edge of the fire box or casing 10 and closed at its upper end except for an entrance opening 12 through which the metal either in lumps or in a molten state is introduced into the said 25 pot, this opening being indicated at 12 and normally closed by a cover 13 held in effective engagement with the pot by means of the threaded element 14. This cover is pivoted on an arm 15 which projects laterally or at a right angle from an operating lever 16, the arm being pivoted as at 17 at one side of the opening, so that the cover 13 together with the lever can be easily moved to uncover the opening, or close the latter as 30 the occasion may require. The lower end of the lever is provided with means 18 for locking the lever in the position illustrated. The outlets for the pot or receptacle 11 consists of a tube 19 which extends from the 35 bottom of said pot along one side thereof, projecting from said pot at a point adjacent the upper end of the casing 10 and communicating with the mold 20.

Arranged above the receptacle or pot 11 is 40 a three-way valve 21 operating within a valve casing 22, the latter being provided with aligned hollow bosses 23 and 24, and an additional boss 25. Depending from the hollow boss 23 is a short pipe connection 26 45 which communicates with the pot or receptacle. Coupled with the hollow boss 24 is a

compressed air supply pipe 27 which leads from any suitable source of supply, while coupled with the boss 25 is the adjacent end of a carbon-dioxide gas supply pipe 28, the latter communicating with a supply tank 29. The valve is provided with a lever 30 so that its respective ports can be brought into proper registration with the receptacle supply pipe in a manner to be presently described, or into communication with the exhaust port 31.

In practice, the cover 13 is unseated or opened to allow the metal either in lumps or in a molten state to be introduced into the pot 11, subsequent to which the cover is closed and locked in the manner above stated. The heat from the burner 33 arranged immediately beneath the pot 11 maintains the metal in a molten state. By 50 operating the valve lever, the valve may be arranged in a set position to admit the carbon dioxide gas to the pot 11 on top of the metal contained therein, prior to the admittance of the compressed air to said pot. The valve lever is then adjusted to seat the valve in another position to introduce into the pot 11 the compressed air, thereby forcing the metal through the outlet conduit into the mold which as shown is coupled with the 55 outlet end of the conduit. The valve lever is then moved to position the valve in an exhaust position, thereby relieving the pressure in the pot, so that the mold may be removed from the nozzle or the adjacent end 60 of the outlet conduit. It is manifest that I have devised a machine of the class in question, wherein the simplicity of operation both in charging and discharging the metal, and also in the combination use of carbon 65 dioxide gas and air under pressure for the transferring of metal under pressure are 70 features of intrinsic value.

While it is believed that from the foregoing description, the nature and advantages 75 of the invention will be readily apparent, I desire to have it understood that I do not limit myself to what is herein shown and described, and that such changes may be resorted to when desired as fall within the 80 scope of what is claimed.

What I claim is:—

A die casting machine comprising a hollow casing, a receptacle having an inlet opening therein mounted in the casing, a lid pivotally mounted on said opening, an operating lever on said lid, a tube vertically

mounted thru the wall of the receptacle adapted to alternately supply compressed air and gas thereto, a three way valve supported by the tube and connected therewith to control the supply of air and gas to the receptacle, and a discharge duct leading from the receptacle to a mold, said duct being formed

on the interior walls of the receptacle and conforming to the curvature of the sides thereof from the bottom to a point near the top.

In testimony whereof I affix my signature.

JAMES BATE.
